GAS SEALED EXPLOSIVE PROPELLING
ARRANGEMENT

Irwin R. Barr, Lutherville, Md., assignor to Aircraft Armaments, Inc., Cockeysville, Md., a corporation of Maryland

Filed June 5, 1961, Ser. No. 114,891
6 Claims. (Cl. 89—1)

This invention relates to gas sealed propelling arrangements, the invention being illustrated as embodied in a separable bolt having an explosive charge which, when selectively actuated, causes the bolt to separate whereby adjacent bulkheads to which the bolt may be connected can be separated.

In explosively actuated separable bolts, as well as other propelling arrangements for various materials to be propelled it is often desirable to seal the generated propelling gases from the surrounding atmosphere, as well as from the material being propelled. It is also often of importance to provide a high initial propelling impulse force on the propelled material.

It is accordingly a feature of the present invention to provide an improved gas sealed propelling arrangement in which a high initial impulse force is exerted on the material being propelled.

In the illustrative embodiment this feature is achieved through the embodiment of an explosive charge actuated gas propelling device, which in the present instance is a separable bolt, and which incorporates a propellable-charge-carrying cup-shaped gas seal having a closed tube end extending toward and adjacent the explosive charge, with gas flow inhibiting or sealing means at this closed tube end of the seal to inhibit or substantially seal off forward gas flow from the explosive charge zone at this closed end to the zone laterally surrounding this charge-carrying tubular portion of the seal during at least the initial portion of longitudinal movement of the tubular portion of the seal, and thereby yielding among its advantages the effecting of a higher initial propelling pressure and propelling force on the closed tube end of the cup seal and the charge of material which is initially carried by and within the tubular portion of the seal than would be present without this gas flow inhibiting or sealing means.

Still other objects and attendant advantages will become apparent to one skilled in the art from a reading of the following detailed description of one preferred physical embodiment constructed in accordance therewith, taken in conjunction with the accompanying drawings wherein:

FIGURE 1 shows separable bolts connecting a two-stage rocket, with parts cutaway to illustrate internal construction.

FIGURE 2 is a sectional view of a separable bolt taken generally along the line 2—2, and showing how the bolt mechanically interconnects adjacent bulkheads.

FIGURE 3 is a sectional view similar to FIGURE 2, but showing how actuation of the bolt causes the mechanical connection between the bulkheads to fail.

FIGURE 4 is a sectional view similar to FIGURE 3, but showing how propellant gases react to thrust the bulkheads apart.

FIGURE 5 shows how all of the propellant gases pro-

2

duced when the bolt is actuated are entirely contained within a closed chamber.

Referring now to FIGURE 1, the interconnection between adjacent stages 10 and 11 of rocket 12 is shown. Both stages are cylindrical and have abutting ends 13. Bulkhead 14 on stage 10 is spaced from bulkhead 15 on stage 11. A plurality of separable bolts 16 interconnect bulkhead 14 to bulkhead 15 such that stages 10 and 11 form an integral structural unit.

Referring now to FIGURE 2, bolt 16 is seen to include tubular sleeve 17 extending between bulkheads 14 and 15. Boss 18 adjacent one end of sleeve 17 abuts bulkhead 14 which has aperture 19 through which the sleeve extends. This end of sleeve 17 is threaded to receive locking unit 20 which securely connects the sleeve to bulkhead 14. The opposite axial end of sleeve 17 is closed and of reduced diameter to form threaded bolt 21 which extends through aperture 22 in bulkhead 15. Lock nut 23 threaded onto bolt 21 securely connects the sleeve to bulkhead 15. In the above manner, the axial ends are rigidly connected to opposite bulkheads.

Sleeve 17 has cylindrical bore 24 with threaded opening 25 at the end of the sleeve connected to bulkhead 14. Closure body 26 is threaded into opening 25 for closing the same, and has an exposed end 27 threaded to receive an electrical connector 28. Stepped recess 29 in closure 26 is provided for electrical primer 30 used to detonate a charge contained in pocket 31 when power is supplied through connection 28 to pins 32 interconnected by bridge wires 33.

Cylindrical push rod 34 is smaller in diameter than the bore. Projection 35 concentric with rod 34 on one end thereof is engaged in recess 36 in the closed end of sleeve 17 adjacent bulkhead 15 to limit movement of the rod toward bulkhead 15. As seen in the drawing, rod 34 is concentric in bore 24 and extends toward closure 26, terminating in a transverse face 37. Any other equivalent connection between rod 34 and bulkhead 15 could be used.

To disconnect bulkheads 14 and 15, weakened portion 38 is provided in sleeve 17 in the form of a circumferential groove. The sleeve thickness is thus locally reduced resulting in failure at the groove when a predetermined force is applied to the bulkheads tending to separate them. Such force is generated by propellant gases acting on casting 39.

Casing 39 is located in bore 24 adjacent the closed end thereof and is interposed between sleeve 17 and rod 34. Casing 39 includes a first tubular section 40 of substantially the same diameter as the bore engaged therein. One end of section 40 is rigidly attached to closure 26 by suitable means. As previously described, closure 26 is rigidly attached to sleeve 17. Section 40 thus extends away from closure 26 and constitutes a portion of the casing that is fixed to the sleeve. Casing 39 also includes a circumferential flange 41, at the end of section 40 remote from closure 26, that extends into the bore at a point axially spaced from the closure. Cylindrical deformable tube 42 having one end connected to flange 41 is a portion of the casing that is concentric with both section 40 and bore 24, and extends toward closure 26 to define annular chamber 50. Tube 42 is engaged with rod 34 for coaxially supporting the same in the bore. The other end of tube 42 has transverse face 43 engaged with face 37 on rod 34.

Face 43 forms a casing closure closing that end of the tube. Thus, the tube forms a portion of the closed annular chamber 50.

Face 43 of the casing is slightly spaced from primer 30 attached to the closure body. However, annular extension 51 on closure 26 extends into annular chamber 50 as best seen in FIGURE 2. Thus, extension 51 effectively separates annular chamber 50 from primary chamber 52 defined in part by the space between face 43 and the closure body. Actually, both primary chamber 52 and annular chamber are small.

In operation, power supplied to pins 32 causes bridge wires 33 to ignite a charge in pocket 31. Because primary chamber 52 is relatively small, the pressure therein reaches a relatively high level exerting on face 43 an axial force directed toward bulkhead 15. Annular extension 51 on the closure body prevents a significant amount of gas from expanding into chamber 50 with the result that a very large axial force is exerted on rod 34 imparting axial movement thereto away from bulkhead 14 since the shoulder connecting rod 34 to extension 35 prevents relative movement of rod 34 toward bulkhead 15. As a result, sleeve 17 fails at groove 38 after initial axial displacement of face 43, tube 42 sliding relative to extension 51.

As shown in FIGURE 3, propellant gases in the primary chamber expand into annular chamber 50 as face 43 is axially displaced beyond the free edge of annular extension 51. Such axial displacement of face 43 along the bore away from the closure deforms tube 42 into another tube substantially the same diameter as the bore that extends from the portion of casing 39 fixed to the sleeve away from the closure. Tube 42, however, remains connected to tube 40 throughout axial displacement of face 43 for entirely containing the propellant gases within a closed chamber. In this way, the energy in the gases is not dissipated as in the normal case, but is used to thrust the rod away from bulkhead 14.

Rod 34 is coaxially supported during axial displacement of face 43 by the portion of tube 42 that remains undeformed prior to maximum axial displacement of the face as can be seen in FIGURE 3. As a result of this construction, the propellant gases react first in a small volume to achieve high pressures and cause a high resultant axial force to be applied to the push rod. This causes failure of the mechanical connection between the bulkheads. Next, the deformable tube coaxially supports the push rod as deformation occurs. All the propellant gases remain confined so that all of the energy in the gases is used to provide a thrust separating the bulkheads.

While the invention has been illustrated with respect to a single physical embodiment constructed in accordance therewith, it will be apparent to those skilled in the art that various modifications and improvements can be made without departing from the scope and spirit of the invention. For instance, other desired charges than a solid rod can be propelled according to this invention, if so desired, and the invention can be practiced in other arrangements than separable bolts. Also, while an electric primer is shown in the illustrative embodiment, a mechanical primer could be used instead. Further propellant gases could be supplied from a gas generator source removed from the connector and acting on the closed end of the tube seal. Accordingly, it is to be understood that the invention is not to be limited by the specific illustrative embodiment, but only by the scope of the appended claims.

What is claimed is:

1. A gas sealed propelling arrangement comprising a casing having a bore formed therein; a cup-shaped diaphragm seal having a longitudinally extending tubular body portion closed at one end and extending lengthwise along a portion of the length of said bore, a transversely out-folded end portion integral with and formed at the opposite end of said tubular body portion, and means

connecting said outfolded end portion to said casing in substantially gas pressure sealing relation; explosive charge gas pressure generating means adjacent said one closed end of said cup-shaped diaphragm seal, an annular pressure seal unit mounted at said one closed end of and in contact with said diaphragm seal extending transversely beyond the end face of said closed end to substantially seal said explosive charge gas pressure generating means from the zone radially external of the circumferentially cuter wall of said tubular body portion, whereby upon actuation of said explosive charge gas pressure generating means the explosive gas pressure action on said tubular portion of said diaphragm is substantially restricted to endwise thrust on said closed end of said tubular portion during at least the initial portion of endwise longitudinal movement of said diaphragm, and a longitudinally propellable charge of material disposed within and carried by said tubular portion of said diaphragm.

2. Apparatus according to claim 1 wherein said propellable charge is a rigid body.

3. Apparatus according to claim 1 wherein said casing encloses said diaphragm and said propellable charge, said casing bore being shorter than the combined effective length of said propellable charge within said bore and the longitudinally out-folded effective length of said diaphragm.

4. Apparatus according to claim 1 wherein said annular pressure seal member is a sleeve surrounding said tubular portion of said diaphragm at said closed end thereof.

5. A gas sealed propelling arrangement comprising a casing having a bore formed therein; a cup-shaped diaphragm seal having a longitudinally extending tubular body portion closed at one end and extending lengthwise along a portion of the length of said bore, a transversely out-folded end portion integral with and formed at the opposite end of said tubular body portion, and means connecting said outfolded end portion to said casing in substantially gas pressure sealing relation explosive charge gas generating means adjacent said one closed end of said cup-shaped diaphragm seal, and external of said tubular body portion, and an annular sleeve separable from said seal and surrounding said tubular portion of said diaphragm at said one closed end thereof and thereby inhibiting gas flow from the zone adjacent said explosive charge gas generating means and one closed end toward said outfolded opposite end portion of said seal to thereby effect an initial higher gas pressure within the zone adjacent said closed end than would otherwise be present without said annular sleeve, and a longitudinally propellable charge of material disposed within and carried by said tubular portion of said diaphragm.

6. A gas sealed propelling arrangement comprising a casing having a bore formed therein; a cup-shaped diaphragm seal having a longitudinally extending tubular body portion closed at one end and extending lengthwise along a portion of the length of said bore, a transversely out-folded end portion integral with and formed at the opposite end of said tubular body portion, and means connecting said outfolded end portion of said casing in substantially gas pressure sealing relation; explosive charge gas pressure generating means adjacent said one closed end of said cup-shaped diaphragm seal, said bore having a first annular confining wall portion disposed about said one closed end of said tubular portion and being substantially complementary to and surrounding the corresponding adjacent circumferential periphery of said tubular portion of said diaphragm, said bore having a second annular confining wall portion disposed contiguous with and extending longitudinally beyond said transversely out-folded opposite end portion of said diaphragm and being of larger diameter than said first wall portion by an amount in excess of the circumferential thickness of said tubular portion of said diaphragm, whereby said first wall portion serves as a gas flow restricting means

and a lateral guide for movement of said tubular portion during at least the initial lengthwise movement of said tubular portion away from said gas pressure generating means, and the relatively larger circumferential size of said second wall portion permitting sequential incremental cold flow rolling out-folding of said tubular portion of said diaphragm to a new inside-out shape bounded by said larger diameter wall portion during longitudinal movement of said diaphragm therethrough, and a longi-

tudinally propellable charge of material disposed within and carried by said tubular portion of said diaphragm.
